FASTENING MEANS FOR U-SHAPED MAGNETS IN MAGNETIC PLATE ASSEMBLIES

Ronald C. Hoff, Erie, Pa., assignor to Eriez Manufacturing Company, Erie, Pa., a corporation of Pennsylvania

Application June 25, 1949, Serial No. 101,433

5 Claims. (Cl. 175—21)

1

This invention relates generally to a magnetic plate assembly and more particularly to novel means for securing U-shaped magnets in a magnetic plate assembly.

Bolt and nut assemblies have heretofore been used for securing U-shaped magnets to a magnetic plate. It has heretofore been necessary to form built up portions on opposite sides of the magnet and core apertures through which the bolts may extend. Magnets now in use, known generally as Alnico magnets, are not machinable and there is considerable difficulty in coring the holes for the bolts. Coring is performed with carbon cores which are expensive in themselves. Furthermore, the grains in the magnet are frequently set up directionally so that they follow the curvature of the magnet. Only the magnetic grains that lie along the line of magnetization are efficiently used. Where the grain structure is in the line of magnetization, the external energy produced is three times that of a similar magnet with the grain structure normal to the line of magnetization. Prior magnets do not provide for the effective use of a magnet with a grain structure in the line of magnetization. Expensive magnetic material must be used in prior magnets to provide bosses for bolt and nut assemblies. In prior magnetic plate assemblies, it has been necessary to form bolt holes in the plate and the head of the bolt projected from the plate so as to provide an uneven surface.

It is, accordingly, an object of my invention to overcome the above and other defects in present magnetic plate assemblies and it is more particularly an object of my invention to provide a magnetic plate assembly which is simple in construction, economical in cost, economical in manufacture, and efficient in operation.

Another object of my invention is to provide novel means for attaching U-shaped magnets to a plate without the use of bolts and nuts.

Another object of my invention is to provide novel means for fastening a U-shaped magnet to a plate wherein no apertured built up portions on the outer side of the magnet are required.

Another object of my invention is to provide a novel magnetic plate assembly wherein means are provided for attaching the magnets thereto without requiring the punching of holes in the plate.

Another object of my invention is to provide a magnetic plate assembly wherein the surface of the plate is smooth and has no projections thereon.

Another object of my invention is to provide a novel spring clip for attaching U-shaped magnets to a plate.

2

Another object of my invention is to minimize the amount of material required in a U-shaped magnet to provide a given magnetic force.

Another object of my invention is to utilize struck out portions of a plate in a magnetic plate assembly to attach the magnets thereto.

Other objects of my invention will become evident from the following detailed description, taken in conjunction with the accompanying drawings, in which

Fig. 1 is a perspective view of a U-shaped magnet used in my novel magnetic plate assembly;

Fig. 2 is a perspective view of a spring clip for attaching a magnet in my novel magnetic plate assembly;

Fig. 3 is a perspective view of the plate in my novel magnetic plate assembly before the magnets are attached thereto;

Fig. 4 is a fragmentary side elevational view of my novel magnetic plate assembly showing the magnets attached to the plate; and

Fig. 5 is a view taken on the line 5—5 of Fig. 4. Referring now to the drawings, I show in Figs.

25 1 to 5 inclusive a non-magnetic plate 1 having laterally and longitudinally spaced, oblong apertures 2 for receiving the end face portions 3 and 4 of U-shaped magnets 5. The plate 1 has oppositely disposed, oppositely struck out portions 6 and 7 parallel to each other and spaced laterally from the apertures 2 in the plate 1.

Each magnet 5 has oppositely disposed, inwardly extending shoulder portions 8 engageable by the offset curved ends 9 of a spring clip or plate 10. The struck out portions 6 and 7 of the plate 1 are bent over opposite sides of the central portion of the clip 10 to secure the magnet 5 in a position as shown in Figs. 4 and 5 with the end faces 3 and 4 extending into the apertures 2 of the plate 1.

The lower portion of the clip 10 is spaced a predetermined distance from the face of the plate 1 when the curved end portions 9 thereof freely rest on the shoulder portions 8 of the magnet 5 so that when the struck out portions 6

30 and 7 are bent over opposite sides of the central portion of the clip 10, it will be forced downwardly thereby tensioning the opposite ends thereof engaging the shoulders 8 of the magnet 5 to secure it firmly on the plate 1. A second plate is disposed

35 adjacent plate 1 and suitable pole pieces are provided on the ends of the pole faces 3 and 4 of the magnet 5 (not shown).

40 It will be observed that the face of the plate 1 will be absolutely smooth inasmuch as there are no projecting bolt heads or any other projecting

45 50 55

portions. My novel fastening device eliminates all bolt and nut assemblies. A maximum amount of the extremely costly magnetic material is eliminated, greatly decreasing the cost thereof. My novel U-shaped magnet without any projections thereon is the closest approach to maximum efficient use of U-shaped magnets inasmuch as the magnetic forces are in the direction of the grain structure of the magnet thereby increasing the efficiency thereof. The outer side of the magnet 5 is smooth and there are only small projecting shoulders 8 on the lower inner sides of the legs of the magnet 5, minimizing any leakage of magnetic lines of force. Fastening members are struck out from the plate 1 thereby saving on material. The clip 10 is extremely simple in design and construction and is very cheap in cost. Assembly of these magnets in my novel magnetic plate is simplified. My magnetic plate may be used as a magnetic separator in a chute or in any other like installation where a smooth magnetic plate is desirable. All coring and other work on the magnet 5 is eliminated thereby further decreasing the cost of the magnet. The amount of the costly magnetic material in the magnet is greatly decreased.

It will be evident from the foregoing description that I have provided a magnetic plate assembly which has novel means for fastening the magnets, which minimizes the cost of the magnet through saving of material and coring operations, which greatly increases the efficiency of the magnets, and one which is extremely simple to produce and assemble.

Various changes may be made in the specific embodiment of my invention without departing from the spirit thereof or from the scope of the appended claims.

What I claim is:

1. In a magnetic plate assembly including a U-shaped magnet and fastening means therefor, in combination, a non-magnetic plate having laterally spaced apertures on opposite sides thereof, opposed, outwardly struck straps transversely of said plate and disposed between said apertures, a U-shaped magnet having the pole faces thereof extending into said laterally spaced apertures and having oppositely disposed, inwardly extending projections on the inner side of the legs thereof, said magnet being mounted on said plate, and a non-magnetic clip spanning said projections and mounted thereon, secured intermittently thereof by said outwardly struck straps of said non-magnetic plate to secure said magnet onto said plate, said straps engaging the side of said clip opposite said plate.

2. In a magnetic plate assembly as set forth in claim 1 wherein the portions of said clip engaging said inwardly directed projections of said magnet are offset.

3. In a magnetic plate assembly including a U-shaped magnet and fastening means therefor, in combination, a flat non-magnetic plate having laterally spaced apertures on opposite sides thereof, opposed, outwardly struck straps transversely of said plate disposed between said apertures, said outwardly struck straps being struck out oppositely to each other in parallel relationship, a U-shaped magnet having the pole faces thereof extending partially into said laterally spaced apertures and having an inwardly directed shoulder on the inner side of each leg thereof, and a non-magnetic clip engaging and spanning said shoulders and mounted thereon secured by said straps on said plate to secure said U-shaped magnet to said plate, said straps extending over and contacting the side of said clip opposite to said plate.

4. A magnetic plate assembly including a U-shaped magnet and fastening means therefor comprising a non-magnetic plate having laterally and longitudinally spaced, rectangular shaped apertures on the sides thereof and opposed, outwardly struck, transversely extending straps between said apertures, U-shaped magnets spaced longitudinally from each other and having the pole faces thereof disposed in the rectangular shaped apertures in said plate for supporting same, the lower inner side of each of the legs of said magnets being offset defining a shoulder, and flexible non-magnetic clips engaging and spanning opposed shoulders on each of said magnets secured by the outwardly struck straps on said plate, the ends of said straps extending over and contacting each of said straps.

5. In a magnetic plate assembly including a U-shaped magnet and fastening means therefor, in combination, a flat non-magnetic plate having laterally spaced apertures on opposite sides thereof, a U-shaped magnet having the pole faces thereof extending partially into said laterally spaced apertures and having an inwardly directed shoulder on the inner side of each leg thereof, a non-magnetic clip engaging and spanning said shoulders and mounted thereon, and fastening members extending outwardly from said plate between said apertures and engaging the intermediate portion of said clip to attach said clip to said plate to secure said U-shaped magnet to said plate.
